TAKEHIRO YAMASHITA, OF KOISHIKAWA-KU, TOKYO, JAPAN

DOUBLE-COLOR MECHANICAL PENCIL OR SHARP PENCIL

Application filed March 28, 1932, Serial No. 601,630, and in Japan August 28, 1931.

This invention relates to a double-color mechanical pencil or sharp pencil, and consists of a barrel, a tubular driving screw having crossing helical grooves on the inner surface thereof, a guide-and-magazine unit made from one blank cut from a sheet metal and having two semi-cylindrical lead magazines and two guide channels, two lead propelling members mounted in said guide channels in the guide-and-magazine unit and each carrying a lead and a resilient engaging member engaging with said crossing helical grooves on the tubular driving screw, and parts being arranged in such manner that two leads may be propelled alternately by rotating the said guide-and-magazine unit in one direction or the other.

One object of the invention is to provide a novel sharp pencil containing black and red leads which can be alternately propelled easily.

Another object of the invention is to provide such double-color sharp pencil which can be manufactured, assembled, and disassembled by most simple operations, and is most durable.

In the accompanying drawings, illustrating what I now consider the preferred form of this invention,

Fig. 1 is a central sectional view through a pencil constructed according to this invention;

Fig. 2 is a central sectional view taken at a right angle to Fig. 1;

Fig. 3 is a cross section on line III—III of Fig. 1;

Figs. 4 and 5 are elevations of the lead propelling members viewed respectively, from opposite sides;

Figs. 6 and 7 are longitudinal sectional views of the members shown in Figs. 4 and 5, at right angles thereto;

Figs. 8 and 9 are, respectively, a front elevation and a side elevation the latter being partly in section of a double guide bar with lead magazines;

Figs. 10 and 11 are elevations showing the method of manufacturing the double guide bar with lead magazine; Fig. 11 showing a

flat blank, and Fig. 10 showing a half made double guide bar with lead magazines.

Fig. 12 is a cross section on the line 12—12 of Fig. 13;

Fig. 13 is an elevation of an eraser holder; 55

Fig. 14 is a cross section on the line 14—14 of Fig. 9;

Fig. 15 is a cross section on the line 15—15 of Fig. 9;

Fig. 16 is a cross section on the line 16—16. 60

According to this invention, two guide bars A, A and two lead magazines B, B are made in one piece from a blank cut from a sheet metal as shown in Fig. 11. The blank is bent along two longitudinal chain lines, thus forming guide channels A, A and two semi-cylindrical portions B, B at opposite ends as shown in Fig. 10 at the left hand side of Fig. 11. Then, it is bent at the mid point with the guide channels A facing outwardly, as shown in Figs. 8 and 9. When cutting the blank tongues 1, 1 are cut out, and they are bent at right angle so as to form bottoms of respective lead magazines as best shown in Figs. 1 and 2. On the lead magazine B, B

grooves b, b are formed so as to constitute an annular groove when the magazines are brought together. At the upper ends of the lead magazines B, B recesses 2, 2 are formed to receive therein an eraser holder C. Said eraser holder C is provided at diametrically opposite sides with longitudinal slots 4 which are adapted to engage with and grip the inwardly bent portions 3, 3 of the lead magazines, whereby said two semi-cylindrical lead magazines are firmly held together. 75

In each of the guide channels formed on the opposite sides of the guide bar A a lead propelling member D is slidably mounted. Said lead propelling member D has a stiffening indentation or embossment 5 and has an upper bent portion 6 which is provided with an engaging ridge 7. Said engaging ridge 7 is inclined and resiliently engages with one of crossing helical grooves formed on the inner side of the driving screw E. To the other end of each propelling member D is secured a flexible rod 8 preferably consisting of a wire rope, which carries at its lower end a lead holder d. In said lead 90

holder *d* is provided a usual means for discharging remaining short lead from the holder *d*.

The tubular driving screw member *E* is formed of a sheet metal worked by pressing and rolling operation, and it has crossing helical grooves *e* on the inner surface thereof. Such crossing helical grooves *e* are shown as crossing helical ridges on the outer surface of the driving member. Near the upper end, the driving screw member *E* is provided on the inner surface with an annular ridge or projection *g*, and there are formed longitudinal slits *h*, *h* diametrically opposite to each other. When the guide-and-magazine unit *A*, *B* is inserted into the tubular driving screw *E*, the annular grooves *b* is engaged by the annular ridge *g*. At the lower end of the driving screw *E*, a hole *i* is formed, which receives a projection *j* formed on a coupling tube *F*. Said coupling tube *F* is provided with a male screw thread *f* on its lower end which protrude beyond the lower end of the barrel *G*, and to which screw thread *f* is screwed a nozzle or end section *H*. *l* designates a cap carrying a clip *14*. *15* is an india-rubber eraser. The leads are designated by *16*, *16*.

According to this invention, by removing the end section *H* all inner parts can be readily detached. For assembling the parts, the eraser holder *C* is inserted in the upper end of the guide-and-magazine unit *A*, *B* with the slits *4*, *4* engaging the bent portion *3* on the magazine. Two lead propelling members *D*, *D* are mounted in the guide channels in the guide bar *A*. Then the guide-and-magazine unit *A*, *B* is inserted into the tubular driving screw *E*, with the annular groove *b* engaged by the inner annular ridge *g* on the tubular driving screw *E*. The joint tube *F* is screwed to the lower end of the tubular driving screw *E*, and the whole is inserted into the barrel *G*. Then, by screwing the end section *H* on the lower end of the joint tube *F* which protrudes beyond the lower end of the barrel, all the inner parts are firmly assembled. The cap *13* is mounted on the projecting upper portion of the magazine *B*. It will be seen from the foregoing that by rotating the guide-and-magazine unit *A*, *B* in one direction or the other by means of the cap *13*, one of the lead propelling members *D*, *D* will proceed while the other recedes. Thus, one may alternately use the desired one of the leads.

Inasmuch as two lead magazines and two guide bars are made from a one piece blank cut from sheet metal, the manufacture thereof is most simple. The parts being assembled by groove-and-ridge connection and by hole-and-projection connection, not using any solder or any other uniting means, the parts may be disassembled easily, and breakage may be reduced to a minimum. Inas-

much as the engaging ridge *7* of the lead propelling member *D* yieldingly engage with the helical groove *e* on the driving screw *E* on account of the resiliency of the bent portion *6*, and said resiliency is limited by the embossment or indentation *5*, which, being in the nature of a corrugation, stiffens the part and as the lead holder *d* is carried by a flexible rod *8*, a soft and reliable action can be expected in propelling the leads, and breakage of the leads is reduced to minimum.

What I claim is:

1. In a double-color sharp pencil, a guide-and-magazine unit made from one blank cut from a sheet metal and having two semi-cylindrical lead magazines and two guide channels, lead propelling members respectively mounted in said guide channels, and a tubular driving screw having crossing helical grooves engaging with said lead propelling members.

2. In a double-color sharp pencil, a guide-and-magazine unit made from one blank cut from a sheet metal and having two semi-cylindrical lead magazines provided with an annular groove and two guide channels, lead propelling members respectively mounted in said guide channels, a tubular driving screw having crossing helical grooves engaging with said lead propelling members and having an inner annular ridge engaging with said annular groove on the magazines, and means for holding said two semi-cylindrical lead magazines together.

3. In a double-color sharp pencil, a barrel, a tubular driving screw having near one end a hole, a guide-and-magazine unit inserted in said tubular driving screw, a coupling tube having a projection engaged by said hole in the driving screw, and a nozzle screwed on the free end of the said joint tube protruding from the barrel.

4. In a double-color sharp pencil, a barrel, a tubular driving screw having near one end a hole, a guide-and-magazine unit made in one piece having two guide channels and inserted in said tubular driving screw, lead propelling members mounted in said guide channels, a coupling tube having a projection engaged by said hole in the driving screw, and a nozzle screwed on the free end of said joint tube protruding from the barrel.

5. In a double-color sharp pencil, a guide-and-magazine unit made from one blank cut from a sheet metal and having two semi-cylindrical lead magazines and two guide channels, and an eraser holder having two longitudinal slits adapted to grip the said two semi-cylindrical lead magazines together.

6. In a double-color sharp pencil, two lead propelling members each having a stop and an upper resilient bent portion carrying an inclined engaging ridge, and a tubular driv-

ing screw having crossing helical grooves adapted to be yieldingly engaged by said engaging ridges on the lead propelling members.

7. In a double-color sharp pencil, a lead holder, a lead propelling member, a flexible lead consisting of a wire rope and connecting said lead propelling member and the lead holder, and means for discharging the remaining short lead from said lead holder.

In testimony whereof I affix my signature.

TAKEHIRO YAMASHITA.
